(57) **CLAIM**

The ornamental design for the archery bow forearm rest as shown and described.

DESCRIPTION

FIG. 1 is a front view of the archery bow forearm rest of the present invention; and

FIG. 2 is a rear end view thereof; and

FIG. 3 is a left side view thereof; and

FIG. 4 is a right side view thereof; and

FIG. 5 is bottom view thereof; and

FIG. 6 is a top view thereof; and

FIG. 7 is a perspective view thereof; and,

FIG. 8 is a perspective view thereof operably coupled to an exemplary archery bow.

Wherein the broken lines herein illustrate use and environment and form no part of the claimed design.
